OF PHILADELPHIA, PENNSYLVANIA, A CORPORATION OF DELAWARE.

VACUUM-CLEANER.

1,152,025.

Specification of Letters Patent. Patented Aug. 31, 1915.

Application filed September 28, 1910. Serial No. 584,191.

To all whom it may concern:

Be it known that we, JULIUS KELLER and JOSEPH H. TEMPLIN, citizens of the United States, residing in the city and county of 5 Philadelphia, State of Pennsylvania, have invented a new and useful Vacuum-Cleaner, of which the following is a specification.

Our present invention relates to that class 10 of devices for removing dust, in which a partial vacuum is produced in a chamber having an air-filtering apparatus, by means of a pumping apparatus connected to such chamber, and in which dust is sucked, together with air, into such chamber through 15 a nozzle and hose and thus separated from the air, or the so-called vacuum cleaners.

Our invention consists of a novel means for absorbing vibration of the motor actuating the pumping apparatus in such vacuum 20 cleaners and deadening the noise by the operation of such motor.

Our invention further consists of novel means for supporting the pumping apparatus in such vacuum cleaners.

25 Our invention further consists of novel means for suspending the pumping apparatus in such vacuum cleaners and absorbing the vibration in the same by the action of the operating pumping apparatus itself.

30 Our invention further consists of novel means for preventing injury to the pumping apparatus in such vacuum cleaners from sudden shocks.

It further consists of other novel features 35 of construction, all as will be hereinafter fully set forth.

For the purpose of illustrating our invention we have shown in the accompanying drawing one form thereof which is preferred by us, since the same has been found 40 in practice to give satisfactory and reliable results, although it is to be understood that the various instrumentalities of which our invention consists can be variously arranged and organized and that our invention is not limited to the precise arrangement and organization of these instrumentalities as herein shown and described.

Figure 1 represents an axial vertical section 45 of a vacuum cleaner embodying our improvement. Fig. 2 represents a side elevation, partly in section, of the suction cham-

ber and the supports for the latter and for the motor.

Similar numerals of reference indicate 55 corresponding parts in the figures.

Referring to the drawings: The illustrated machine has a circular base, 1, preferably mounted on casters, 2, and which is formed with an upstanding flange, 3. A cylindrical 60 casing, 4, has a bottom ring, 5, which is formed with an annular groove, 6, in which fits a yielding gasket, 7, which rests upon the upstanding flange of the base. The base has pivoted bolts, 8, provided with 65 thumb-nuts, 9, and said bolts and nuts engage slotted lugs, 10, upon the bottom ring of the casing, so as to tightly draw the gasket against the flange and thus tightly close the joint between the casing and the base. 70 Handles, 11, are secured to the sides of the casing. The upper end of the casing is closed by a cover, 12, having slotted lugs, 13, engaged by pivoted bolts, 14, and thumb-nuts, 15, and having a handle, 16, across the 75 top. The cover has an inlet opening, 17, to which the suction-hose carrying the dust-laden air may be connected. The inlet opening leads into an inverted truncate conical chamber, 18, which opens into the interior 80 of the casing and is covered by an observation glass, 19, through which the dust-laden air entering the machine may be observed. A metallic ring, 20, is clamped between the cover and the top ring of the casing, and gaskets, 21, are fitted in grooves in the cover and top ring to provide a tight closure at the joint. A bag, 22, of textile 85 material is secured to the ring to depend into the casing, and another bag, 23, of a 90 textile material of finer mesh or texture than that of the inner bag, is supported by its top wire upon a shoulder, 24, within the casing.

A slightly dished partition, 25, is secured 95 to the wall of the casing at about the middle of the same, and divides the casing into two chambers, the upper one, 26, of which will hereafter be referred to as the vacuum chamber, and the lower chamber as the pressure chamber, 27. The pressure chamber has a restricted outlet through an opening, 27^x, in its side, and to which a hose may be connected when a blast of air is required. 100

The partition has a central opening, 28, through which communication is made between the two chambers, and said opening is surrounded by a slightly upturned flange, 29. A foraminated plate, 30, rests upon the partition above the central opening, to prevent the bags from being drawn through the latter.

The pumping apparatus is suspended in the pressure chamber in a manner later herein to be described, and has a suction chamber, 31, of circular outline, inclosed by a domed top, 32, and a band, 33, having each laterally projecting annular flanges, respectively, 34 and 35, which are secured together and clamp the edge of a flexible diaphragm, 36, between them. The domed top has a central intake opening, 37, having an upturned flange, 38, and a slightly dished, annular suction cup, 39, of rubber or similar yielding, flexible and elastic material, fits around said flange and is held in place by rings, 40, and bolts, 41, which clamp the cup and the top between the rings. The cup is preferably thicker at the center than at the edges, so that said thinner edges may closely fit and bear against the under side of the dished partition around the opening in the same, when suction is created in the suction chamber,—the cup thus forming a flexible and yielding adhesion chamber. An inwardly-opening valve for the pumping chamber is formed by a seat plate, 42, having a number of perforations, 43, a flexible diaphragm, 44, having a number of perforations, 45, arranged in staggering alinement with those in the seat plate, and a perforated guard plate, 46. Said valve is secured within the domed top, beneath the suction opening in the same, by clamping rings, 47, clamping the edges of the plates and diaphragm and bolts or rivets 48, through the top, plates, diaphragm and rings. A central post, 48*, secured to the two plates, spaces the same at their middles to maintain free space for the play of the diaphragm. A similar valve is formed in the pump diaphragm 36 by means of a seat plate, 49, having a number of perforations, 50, the middle portion of the pump diaphragm having a number of staggered perforations, 51, and a foraminated plate, 52. Said parts are secured together at their edges and to an annular follower, 53, by means of bolts or rivets, 54, and the middles of the plates are spaced by a central post, 55, to allow free space for the play of the diaphragm.

A motor, 56,—in the present instance, an electric motor,—is supported below the pumping chamber in a manner hereinafter to be described. The motor shaft, 57, has secured upon its ends fly-wheels, 58, and eccentric disks, 59. The eccentric straps, 60, of two pitmen, 61, fit around the disks, 65 and anti-friction balls, 62, are placed in a

ball-race between each strap and the rim of the disk. The upper ends of the pitmen are connected to ears, 63, depending from the follower, 53, by pins, 64, and the follower and the diaphragm will be reciprocated from the rotary motion of the motor through the eccentrics and pitmen.

Upright rods, 65, are secured at their lower ends in the base of the machine and have tubular sleeves, 66, upon their lower portions. The flanges of the suction chamber and the diaphragm have holes, 67, through which said rods pass, so that said chamber may have vertical movement upon the rods. Coiled springs, 68, upon the rods, bear against the upper ends of the sleeves upon the rods and against the flange of the suction chamber, so as to yieldingly support the latter, and coiled springs, 69, upon the rods, bear from above against the flange of the suction chamber and are held at their upper ends by nuts, 70, upon the rods. Brackets, 71, have their upper ends secured to the flange of the suction chamber, and converge slightly to be secured to a bottom-plate, 72, upon which the motor is supported and secured, so that the entire pumping apparatus is yieldingly supported upon the springs upon the rods and is guided in its vertical movement by said rods. Normally the springs hold the pumping apparatus just sufficiently high to bring the edge or lip of the suction-cup in contact with the partition in the casing between the vacuum chamber and the pressure chamber. A tubular block, 73, of rubber or other resilient material, is secured upon a stud, 74, projecting downward from the under side of the bottom-plate, and said block is guided within a socket, 75, in the base, and does not normally touch the bottom of such socket, but simply serves as a buffer to cushion the bracket support or cage on excessive downward movement of the same.

In practice, a hose provided with a suitable suction nozzle (not shown) is connected to the inlet opening in the cover, and connection by wire (not shown) is made to the motor from a suitable supply of electricity, such as an ordinary lamp socket. When now the motor is started, the diaphragm in the suction chamber will be rapidly reciprocated or vibrated, drawing in air through the inlet valve in the top of the chamber, the diaphragm of which valve will be drawn inward to admit air on the downward stroke of the pump diaphragm and forced upward to close the staggered openings of the valve on the upward stroke of the pump diaphragm. Likewise, the valve formed by the pump diaphragm will be opened on the upward stroke of the latter, expelling air into the pressure chamber, and will be closed on the downward stroke to create suction in the chamber. The suction created in the suc-

tion chamber will cause the suction cup to tightly bind against the partition, and the pumping apparatus will be supported from the partition by the suction cup, which will take the weight off from the lower springs. As the pumping apparatus operates, a partial vacuum will be created in the vacuum chamber and, when the suction nozzle is properly applied, dust-laden air will be drawn in through the inlet opening, into the vacuum chamber, where it will be filtered through the dust bags, drawn through the suction chamber, forced into the pressure chamber, and finally be expelled through the outlet opening. As the vacuum chamber has a restricted inlet, it is evident that the pumping apparatus will maintain a partial vacuum in said chamber, and it is likewise evident that pressure above that of the atmosphere will be maintained in the pressure chamber owing to the latter having a restricted outlet, and that such difference of pressure will bind the suction cup to the partition.

The entire pumping apparatus and, especially, the motor being suspended by yielding support consisting of the springs and the suction cup, it is evident that all vibration caused by the operation of the motor will be absorbed by such yielding support, thereby doing away with two objections heretofore raised against the use of vacuum cleaners of this type, namely, the shaking or vibration imparted to the floor and surrounding objects, and the noise caused by the motor resting upon a solid support.

The upper springs upon the vertical rods serve to cushion upward movement of the pumping apparatus, as does also the suction cup. This latter cup is principally relied upon to suspend the pumping apparatus when in operation and to form a vacuum adhesion cushion to absorb vibration. The lower springs support the pumping apparatus when at rest and both sets of springs serve, besides their cushioning function, to relieve or overcome friction between the holes in the flanges and the rods upon which the pumping apparatus is vertically guided, and to balance said apparatus. In case of excessive downward movement of the pumping apparatus, either when in motion or, for example, the entire machine is lifted and set down abruptly, the buffer block or cushion upon the bottom of the supporting frame or cage will cushion the pumping apparatus against excessive shock.

The dust bags are accessible by removing the cover, when they may be lifted out and emptied or whatever else is desired or required. The motor and other parts of the pumping apparatus are accessible by unscrewing the thumb-nuts at the base and removing the casing from the base, and the

entire pumping apparatus may be detached by unscrewing the nuts upon the guide rods and lifting the apparatus from the same.

It will now be apparent that we have devised a novel and useful construction of a vacuum cleaner which embodies the features of advantage enumerated as desirable in the statement of the invention and the above description, and while we have, in the present instance, shown and described a preferred embodiment thereof which has been found in practice to give satisfactory and reliable results, it is to be understood that the same is susceptible of modification in various particulars without departing from the spirit or scope of the invention or sacrificing any of its advantages.

Having thus described our invention, what we claim as new and desire to secure by Letters Patent is:

1. A vacuum cleaner including in combination, a casing forming a vacuum chamber, a pump casing having an intake opening formed therein and in line with the outlet opening of the vacuum chamber, and connecting means operated upon by suction for connecting the pump casing to the casing for the vacuum chamber and independent means for moving said connecting means into contact with the casing.

2. A vacuum cleaner including in combination, a casing forming a vacuum chamber, a pump casing having an intake opening formed therein and in line with the outlet opening of the vacuum chamber, and a yielding and elastic cup connected to the pump casing and surrounding the outlet opening in the casing of the vacuum chamber, said cup being held to the casing by the suction of the vacuum chamber, and independent means for moving said cup into contact with the casing.

3. A vacuum cleaner including in combination, a casing forming a vacuum chamber, a pump casing beneath the vacuum chamber and having its intake registering with the outlet of the vacuum chamber, a pump supported by the pump casing, and means operated upon by the suction in the vacuum chamber for connecting the pump casing to the casing of the vacuum chamber, whereby the pump is yieldingly suspended by its own suction from the casing of the vacuum chamber.

4. A vacuum cleaner including in combination, a casing forming a vacuum chamber, a pump casing beneath the vacuum chamber and having its intake registering with the outlet in the vacuum chamber, a yielding and flexible cup attached to the pump casing and surrounding the outlet in the vacuum chamber, said cup being adapted to engage the casing of the vacuum chamber and support the pump casing, and a pumping mechanism carried by the pump casing.

5. A vacuum cleaner including in combination, a casing forming a vacuum chamber, said casing at the lower face of the vacuum chamber being dished and formed with a central outlet opening, a pump casing beneath said chamber and having its intake registering with said opening, a pumping mechanism supported by the pump casing, and means operated upon by the suction 10 of the pump for yieldingly supporting the pump casing from the casing of the vacuum chamber.

6. A vacuum cleaner including in combination, a casing forming a vacuum chamber, 15 said casing at the lower face of the vacuum chamber being dished and formed with a central outlet opening, a pump casing beneath said chamber and having its intake registering with said opening, a pumping 20 mechanism supported by the pump casing, means operated upon by the suction of the pump for yieldingly supporting the pump casing from the casing of the vacuum chamber, and means for yieldingly supporting 25 the pump casing when the pump is not in action.

7. A vacuum cleaner including in combination, a casing forming a vacuum chamber, a pump casing having an intake registering with the outlet in the vacuum chamber, means for connecting the intake of the pump casing with the outlet of the vacuum chamber, said means being so constructed as to allow the pump casing to move relative to 35 the casing of the vacuum chamber, a pumping mechanism supported by the pump casing, and means for yieldingly supporting the pump casing.

8. A vacuum cleaner including in combination, a casing forming a vacuum chamber, 40 a pump casing having an intake registering with the outlet in the vacuum chamber, means for connecting the intake of the pump casing with the outlet of the vacuum chamber, said means being so constructed as to allow the pump casing to move relative to the casing of the vacuum chamber, a pumping mechanism supported by said pump casing, and springs engaging the pump casing 45 for yieldingly holding the same in a predetermined position relative to the casing of the vacuum chamber.

9. In a vacuum cleaner, a vacuum chamber having an outlet opening, a suction 55 pump beneath said chamber and having its intake registering with said opening, a motor beneath said pump and operatively connected to and supported from said pump, means for yieldingly supporting the pump, 60 and independent yielding means connecting the intake of the pump and the opening of the vacuum chamber.

10. In a vacuum cleaner, a vacuum chamber having a dished bottom formed with a 65 central outlet opening, a pump having its

intake registering with the outlet opening, a yielding suction cup secured around said intake and its edge engaging the bottom of the vacuum chamber around the central opening, a motor operatively connected to 70 and supported from the pump, and yielding means supporting the pump.

11. In a vacuum cleaner, a vacuum chamber having a dished bottom formed with a central outlet opening, a pump having a 75 casing formed with an intake registering with said opening and with a lateral flange, a yielding suction cup secured around the intake of the pump and having its edge engaging the bottom of the vacuum chamber 80 around the central opening, guide rods through the flange of the pump casing, springs upon said rods and bearing against the flange, and a motor operatively connected to the pump and suspended from the 85 casing.

12. In a vacuum cleaner, a pump having a casing, yielding means for supporting said casing, a cage secured to the casing and depending from the same, an elastic buffer 90 secured to the under side of the bottom of said cage, and a motor supported in said cage and operatively connected to the pump.

13. In a vacuum cleaner, a base formed with a central socket, upright rods upon 95 said base, a pump having a casing formed with a lateral flange having holes sliding upon said rods, springs upon said rods and bearing against said flange, a cage secured to the casing and depending from the same, a yielding buffer upon the under side of the bottom of the cage and projecting into the socket of the base, and a motor supported in the cage and operatively connected to the pump. 100

14. In a vacuum cleaner, a casing having a vacuum chamber in its upper portion formed with a restricted inlet and a pressure chamber in its lower portion formed with a restricted outlet, a partition between said 110 chambers and formed with an opening, a suction pump within said pressure chamber, yielding means connecting the intake of the pump to the opening in the partition, and yielding supports for said pump. 115

15. In a vacuum cleaner, a vacuum chamber, a pressure chamber, a partition between said chambers and formed with an opening, a suction pump within the pressure 120 chamber and delivering into the same, and a yielding vacuum adhesion member connecting the opening in the partition and the intake of the pump and secured to one of said elements and adhering to the other by internal suction and external pressure. 125

16. In a vacuum cleaner, a vacuum chamber, a pressure chamber, a partition between said chambers and formed with an opening, a suction pump within the pressure chamber and delivering into the same, 130

and a yielding cup around the intake of the pump and the opening in the partition and secured to one of said elements and adhering to the other by internal suction and external pressure.

17. In a vacuum cleaner, a vacuum chamber, a pressure chamber, a partition between said chambers and formed with an opening, a suction pump within the pressure chamber and delivering into the same and having its intake registering with the opening in the partition, and a yielding vacuum adhesion member connecting said intake and opening and secured to one of the elements and adhering to the other by internal suction and external pressure.

18. In a vacuum cleaner, an upper vacuum chamber, a lower pressure chamber, a horizontal partition between said chambers and formed with an opening, a suction pump in the pressure chamber and having its intake registering with the opening in the partition and delivering into the pressure chamber, and a yielding cup connecting the intake to the opening in the partition and secured to one of the elements and adhering to the other by internal suction and external

pressure, whereby the pump is yieldingly suspended by its suction from the vacuum chamber and its compression into the pressure chamber.

19. In a vacuum cleaner, a casing, a horizontal partition in said casing formed with a central opening and dividing said casing into a vacuum chamber and a pressure chamber, a pump in the pressure chamber and having its intake registering with the opening in the partition and delivering into the pressure chamber, a motor operatively connected to said pump and supported by the same, means for yieldingly supporting the pump, and a yielding vacuum adhesion member secured to the intake of the pump and adhering to the partition around the opening in the same by the suction of the pump from the vacuum chamber and the external pressure upon it from the pump pressure in the pressure chamber.
